Des. 202,270
Patented Sept. 14, 1965

202,270

CABINET UNIT FOR MEDICAL, DENTAL OR SIMILAR USE

Samuel Federman, 7620 Front St., Cheltenham, Pa.

Filed July 3, 1964, Ser. No. 80,692

Term of patent 14 years

(Cl. D24—1)

Fig. 1

Fig. 5

Fig. 2

Fig. 3

Fig. 4

FIG. 1 is a front perspective of a cabinet unit for medical, dental or similar use showing my new design;

FIG. 2 is a top plan view thereof;

FIG. 3 is a front elevation thereof;

FIG. 4 is a side elevation as seen from the left of FIG. 1; and

FIG. 5 is a side elevation as seen from the right of FIG. 5.

The dominant features of my design reside in the portions shown in full lines.

I claim:

The ornamental design for a cabinet unit for medical, dental or similar use, as shown and described.
